M. HIRSCH

ENGINE STARTING APPARATUS

Filed Aug. 5, 1919

INVENTOR
MORRIS HIRSCH

BY *John G. Davis*
ATTORNEY

UNITED STATES PATENT OFFICE.

MORRIS HIRSCH, OF NEW YORK, N. Y., ASSIGNOR TO BIJUR MOTOR APPLIANCE COMPANY, A CORPORATION OF DELAWARE.

ENGINE-STARTING APPARATUS.

Application filed August 5, 1919. Serial No. 315,515.

To all whom it may concern:

Be it known that I, MORRIS HIRSCH, a citizen of the United States, residing at New York city, in the county of New York and 5 State of New York, have invented certain new and useful Improvements in Engine-Starting Apparatus, of which the following is a clear and exact description, such as will enable others skilled in the art to which it 10 appertains to make and use the same.

This invention relates to engine starters more particularly of the type in which an electric motor transmits the cranking torque through a spring.

15 One of the objects of the invention is to provide compact apparatus of the above type which shall deliver the requisite cranking torque by the use of a motor of reduced power.

20 Another object is to provide apparatus of the type mentioned which shall operate with lessened shock even under adverse conditions of operation.

Other objects will be in part obvious and 25 in part pointed out hereinafter.

The invention accordingly consists in the features of construction, combinations of elements and arrangement of parts which will be exemplified in the construction herein- 30 after set forth, and the scope of the application of which will be indicated in the following claims.

In the accompanying drawings in which are shown one or more of various possible 35 embodiments of the several features of my invention, Fig. 1 is a view in longitudinal section of an inboard embodiment, the device being shown out of operative relation, Fig. 2 is a detailed sectional view taken along the 40 line 2—2 of either Fig. 1 or Fig. 4, Fig. 3 is a detailed sectional view taken along the line 3—3 of Fig. 4 and Fig. 4 is a view similar to Fig. 1 of an outboard embodiment of a modified form of the invention, the pinion 45 being shown in mesh with the fly-wheel gear.

Referring now to Figs. 1, 2 and 3 of the accompanying drawings there is shown a motor 1 having a smooth extended shaft 2. Encircling the shaft there is a sleeve or shaft 50 3 threaded as at 4 and connected to be yieldingly driven by shaft 2. This connection comprises a bolt 5 extending transversely through a barrel member 6, and having an inclined surface 7 adapted to be wedged 55 against flat 8 near one end of the shaft ex-

tension, said bolt being secured by means of a nut 9. Encircling the barrel there is provided a coil torsion spring 10 preferably formed of a ribbon of metal elliptical in cross section, with the successive convolutions slightly spaced from each other. The spring 10 is secured at one end by means of the nut 9 to the bolt 5 and is secured at the other end to the adjacent end of the sleeve 3 by means of a screw 11. Directly upon 60 the shaft 2 and beyond the sleeve 3 I provide a driving pinion 12 adapted to mesh with the teeth of preferably a fly-wheel gear 13. A nut 14 is threaded upon the sleeve and is rigidly connected to the adjacent end 70 of the pinion by means of a coupling collar 15 attached to the pinion by any desired means as at 25 and to the nut as at 26. A stop shoulder 16 adjacent the motor arrests the pinion in its movement toward mesh. 75 The stop may if desired be provided on the sleeve for arresting the nut when the pinion reaches mesh, as in the co-pending application of Harold M. Martin, Serial No. 315,532, filed August 5, 1919. The nut may 80 if desired have an eccentric counter-weight 17 as shown.

In operation, upon starting of the motor the shaft 2 drives the sleeve or shaft 3 through spring 10, and the inertia of the nut 85 14 with the attached pinion 12 prevents the transmission member from immediately rotating with the sleeve. The transmission consequently moves forwardly into mesh with the fly-wheel, being limited against 90 further movement when in mesh by contact of the face of the pinion with stop 16. As the nut can then no longer move longitudinally of the shaft, the rotation of said shaft is transmitted through the spring 10 to the 95 sleeve, the nut and the pinion to crank the engine. After starting of the engine under its own power, the nut is caused to overrun the threaded sleeve in the well understood manner drawing the pinion out of mesh with 100 the fly-wheel.

In Fig. 4 I have shown a modified form of my invention carried out in an outboard embodiment. Corresponding parts bear the same reference characters as in Fig. 1, 105 primed however, and those elements which are duplicated in Fig. 1 are not here again described. A housing 24 secured to the motor supports the free end of shaft 2¹.

Provision is made for making possible a 110

limited longitudinal movement of the nut 14¹ with respect to the pinion 12¹. For this purpose the nut is provided with splines 18 fitting in longitudinal slots 19 in the coupling element 15¹. Interposed between the pinion and the nut and within the coupling collar 15¹ I provide compression spring means preferably in the form of a plurality of annular dished washers 20 facing in alternately opposite directions one contacting the nut and one contacting the pinion. The coupling collar 15¹ is rigidly secured to the pinion by any desired means as at 25¹ and the nut 14¹ is prevented from slipping out of the coupling collar by the use of a split ring 21 having lugs 22 extending through openings 23 in the coupling collar 15¹.

The normal operation of the construction of Fig. 4 is obvious from the description of 20 the operation of Fig. 1 above.

In case teeth of pinion 12¹ should abut against teeth of the fly-wheel in moving toward mesh, the pinion is arrested against further movement. The threaded sleeve or 25 shaft will, however, continue to be rotated within the nut by torque transmitted from the motor through spring 10¹, causing said nut to move longitudinally upon the sleeve and along slots 19 thereby compressing 30 springs 20, the sleeve itself moving in a direction to close up the convolutions of the spring 10¹. When springs 20 have been sufficiently compressed to prevent further translation of the nut, the latter will be 35 compelled to rotate with the spring driven threaded sleeve, imparting said rotation through the splines at 19 to the connecting collar 15¹ to rotate the pinion. After slight rotation the teeth of the pinion are in proper 40 alignment between teeth of the fly-wheel, whereupon compression springs 20 and torsion spring 10¹ will expand to urge the pinion into incipient mesh with the fly-wheel gear. Further movement toward full mesh, 45 cranking and demeshing are obvious from the above description.

During normal cranking action as is apparent, compression springs 20 may yield somewhat depending upon the stiffness of 50 the engine.

If the driving pinion were mounted upon

the threaded sleeve instead of directly upon the extended motor shaft it is apparent that such pinion would be larger in diameter and that consequently a lesser torque multiplication would be possible and, therefore, a larger motor would be necessary for a given cranking torque. 55

It will thus be seen that there is herein described apparatus in which the several 60 features of this invention are embodied, and which apparatus in its action attains the various objects of the invention and is well suited to meet the requirements of practical use. 65

As many changes could be made in the above construction and many apparently widely different embodiments of this invention could be made without departing from the scope thereof, it is intended that all 70 matter contained in the above description or shown in the accompanying drawings shall be interpreted as illustrative and not in a limiting sense.

Having thus described my invention, what 75 I claim as new and desire to secure by Letters Patent is:—

1. A starter for engines comprising a motor, a threaded shaft, means for yieldingly driving said shaft from said motor, a nut 80 threaded on said shaft, a toothed driving member coaxial with said nut and beyond the threads of said shaft, a driving connection between said nut and said toothed member, said shaft serving as a stop for said 85 driving member and a compression spring interposed between said nut and said driving member.

2. A starter for engines comprising a motor, a shaft adapted to be driven thereby, a 90 member movable along and with said shaft, a pinion controlled by said member, and means responsive to a butting of the pinion, to shift said member in one direction and said shaft in the opposite direction, and two 95 springs one adapted to be distorted by the shifting of said member and the other by the movement of said shaft.

In testimony whereof, I have signed my name to this specification this 15th day of July, 1919.

MORRIS HIRSCH.
